US0D1084077S

(12) **United States Design Patent** (10) Patent No.: **US D1,084,077 S**
(45) Date of Patent: ** Jul. 15, 2025

(54) **MOBILE DRIVE UNIT**

(71) Applicant: **Amazon Technologies, Inc.**, Seattle, WA (US)

(72) Inventors: **William Clem**, Seattle, WA (US); **Nicholas Van Stolk**, Cincinnati, OH (US); **Matthew Anthony Brady**, Boston, MA (US); **Dincer Bozkaya**, Andover, MA (US); **Gabriel Hebert**, Wakefield, MA (US); **Jefferson Lee**, Chelsea, MA (US); **Mark Anthony Begley**, Brighton, MA (US)

(73) Assignee: **Amazon Technologies, Inc.**, Seattle, WA (US)

(**) Term: **15 Years**

(21) Appl. No.: **29/990,082**

(22) Filed: **Feb. 19, 2025**
